UNITED STATES PATENT OFFICE

2,262,854

PROPELLER DRIVE

Warren T. Morris, Springfield, Mo.

Application October 15, 1940, Serial No. 361,302

2 Claims. (Cl. 170—159)

This invention relates to a power boosting device for propellers.

An object of the invention is to provide a new and improved means for increasing the efficiency of any propeller, or fan, preventing the loss of power by reducing turbulence in the immediate vicinity of said propeller or fan.

Another object of the invention is to reduce the tip loss at the end of the propeller or fan, due to the action of the novel structure of the vanes, and preventing the air from moving away from the propeller blades.

A still further object of the invention is to increase the efficiency of the propeller due to the compressibility effect produced by the novel construction, causing the air to flow through the propeller, and the vanes located aft of the propeller.

With the foregoing and other objects in view, the invention comprises certain novel constructions, combinations, and arrangements of parts as will be hereinafter fully described, illustrated in the accompanying drawings, and more particularly pointed out in the appended claims.

In the drawings:

Figure 1 is a view in front elevation of a device constructed in accordance with present invention.

Figure 2 is a view in side elevation.

Figure 3 is a fragmentary perspective view of the device.

Figure 4 is a perspective view of one of the vanes.

Figure 5 is a view in front elevation of another embodiment of the present invention, while

Figure 6 is a side view thereof.

Figure 7 is a view in side elevation of another embodiment of the invention.

Figure 8 is a view in front elevation of another embodiment of the invention.

Figure 9 is a sectional view taken on line 9—9, Fig. 8, looking in the direction of the arrows.

Referring to the drawings by numeral, 1 designates the hood of an airplane motor, of any desired construction. The propeller 2 extends beyond hood 1, and said propeller includes the blades 3, in all the embodiments of this invention.

Referring specifically to the embodiment shown in Figures 1 to 4, each vane 4 comprises an elongated flat straight body 5 which is provided on its inner end with an integral right-angled base flange 6. A broad curved fin 7 is formed on the outer end of body 5; this fin 7 is broader than body 5, with an overhanging shoulder 8, under which the outer ends of blades 3 pass. Any number of vanes 4 can be placed upon the hood 1,

with their base flanges 6 securely fastened to the hood in any suitable manner. The curved fin 7 extends in opposite direction to the line of rotation of the propeller, as is clearly seen by referring to the arrows A in Fig. 1.

In the embodiment shown in Figures 5 and 6, each vane 9 comprises a straight elongated flat body 10; each body 10 being provided with an integral right-angled base flange 11. Flange 11 is fastened to the hood 1. The inner edge 12 of each vane 10 is curved throughout its length to better adapt it to the propeller 2.

In the embodiment shown in Figure 7, each vane unit 13 comprises a bracket 14, which bracket 14 includes a straight body 15, with an inner right-angled base flange 16, and an outer right-angled flange 17, that overhangs the propeller 2. A vane 18 is attached to flange 17; this vane comprises a curved body 19 that has on its outer end a broad curved fin 20. An overhanging shoulder 21, similar to shoulder 8, is formed on the vane 18. By this peculiar construction, the outer ends of the blades 3 are permitted to pass under the vanes 18, during the rotation of the propeller.

In the embodiment shown in Figures 8 and 9 a plurality of vanes 22 are integrally connected by ring 23. Each vane 22 comprises a bifurcated body 24, including an inner section 25 and an outer section 26. An integral curved fin 27 extends from the outer ends of sections 25 and 26. Each inner section 25 is provided with a right-angled base flange 28. The flanges 28 are fixedly secured in any suitable manner to hood 1. The propeller blades 3 revolve within the structure shown in Figures 8 and 9, between the sections 25 and 26 of vanes 22. As in the case of Figures 1 to 4, the line of rotation of the propeller 2 is opposite to the extended position of the curved fins 27, as indicated by arrow B, Fig. 8.

By reason of the peculiar construction of the vanes, air or water is pulled into the propeller or fan and is prevented from escaping outwardly. The vanes reduced turbulence in immediate vicinity of propeller due to the straightening effect of the vanes located after or before, or both before and after the propeller or fan, as shown in the drawings.

It is to be understood that the vanes do not revolve, but remain stationary at all times. It is also to be understood that if the operator desires, mounting braces and supports (not shown) may be employed to hold the vanes assembled to the plane, or whatever the vanes may be used upon, or in connection with. The accom-

panying drawings show the device on the outlet (Figs. 1 to 6) side of the propeller, or on the inlet side of the propeller (Fig. 7), or on both the inlet and outlet side of the propeller or fan (Figs. 8 and 9).

While I have described the preferred embodiments of my invention and illustrated the same in the accompanying drawings, certain changes or alterations may appear to one skilled in the art to which this invention relates during the extensive manufacture of the same and I, therefore, reserve the right to make such changes or alterations as shall fairly fall within the scope of the appended claims.

What I claim is:

1. In a device of the class described, the combination with a hood and a propeller, of vanes contiguous to said propeller, each vane comprising

an elongated flat body having a broad curved fin at its outer end, part of said fin being laterally-extending and overhanging said propeller, whereby said propeller rotates within a space between the front and rear edges of said fins, and means supporting said vanes upon said hood.

2. In a device of the class described, the combination with a hood and a propeller, of vanes contiguous to said propeller, each vane comprising a body straight throughout its length, a curved fin on the outer end of said straight body, said fin being wider than the outer end of said straight body, whereby a portion of said fin being laterally-extending and overhanging said propeller, and means supporting said vane upon said hood.

WARREN T. MORRIS.
